LIQUID ELEVATING APPARATUS

Filed March 5, 1925

INVENTOR.

13rd H. C. Morrison

Geo. P. Kammel ATTORNEY.

UNITED STATES PATENT OFFICE.

HENRY C. MORRISON, OF LIBERAL, KANSAS.

LIQUID-ELEVATING APPARATUS.

Application filed March 5, 1925. Serial No. 13,248.

This invention relates to liquid elevating apparatus, more particularly to devices of this character associated with wells and the like, and has for one of its objects to improve the action and increase the outflow of the liquid therefrom without material increase of expense or additions to the mechanism employed.

The primary object of the invention is the provision, in a manner as hereinafter set forth, of a pump construction in which the pump pipe or inner casing and valves are enclosed in a sealed air-tight casing to set up, when liquid is drawn from the well, a vacuum in the casing through the removal with the liquid of some of the air therein, thereby causing the liquid to rise higher in the casing than would be the case ordinarily.

With these and other objects in view, the invention consists in certain novel features of construction as hereinafter shown and described, and then specifically pointed out in the claim, and in the drawings illustrative of the preferred embodiment of the invention.

Figure 1 is a vertical section of a conventional well casing and pumping appliance with the improvement applied.

Figure 2 is a transverse section on the line 2—2 of Figure 1, looking in the direction of the arrow.

Figure 3 is a view similar to Figure 1, on a reduced scale, illustrating another means of constructing the improved device.

The structure embodying this invention comprises a well casing 10 of appropriate diameter and which is adapted to extend through a plurality of liquid bearing strata, one arranged above and spaced from the other, said liquid being indicated at 17 in the drawings. The casing is appropriately perforated to provide for the liquid from the liquid bearing strata entering same. As shown, the perforations are indicated at 18 and are arranged in longitudinally spaced groups. The casing 10 is open at its lower end.

The upper end of the casing 10 is screw threaded as indicated at 10', and threaded over this upper end is a closure cap 19 while interposed between the closure cap and the top of the casing 10 is a sealing gasket 20. The cap 19 as shown, has a central passage therethrough and the inner face

of this passage is also provided with a sealing lining 21.

Extending through the passage in the cap 19 and sealed therein, is a pump casing 14 having at its upper end the angled outlet 15 from which a nozzle or other attachment 66 may lead.

Upon the lower end of the pump casing 14 there is secured a valve cylinder 11 in which the valve head 11' is positioned and against the walls of which the packing 12, 65 carried by the valve head 11' bears. The valve head is provided with the usual gravity operated valve 12' and is connected to and is supported by the pump rod 16 which extends upwardly through the pump casing 70 14.

At the lower portion of the cylinder 11 there is located an apertured plate member 23, held against the end of the cylinder 11 by the reducing coupling 24 which is 75 threaded upon the cylinder end as shown. To this coupling a nipple 13' is attached which carries the strainer element 13''.

A longitudinally adjustable sealing element is inserted into the casing 10, in the 80 form of a disc such as that indicated by the numeral 22 in Figure 3, said disc being carried by the pipe casing 14 and having the edge thereof engaging the inner wall of the outer casing 10. This disc is positioned at any desired point between the uppermost 85 group of perforations 18 and the upper end of the casing 10. By employing this sealing element the chamber thereabove becomes a dead air space which can be varied in 90 size by longitudinal movement of the disc and only the air below the sealing element will be exhausted when the pump is operated, thus reducing the area of the inside of the casing which will have the air exhausted 95 therefrom.

By this construction when the pump is first actuated and a portion of the liquid is drawn off, a partial vacuum is produced in the casing 10, and the liquid rises in the 100 casing to fill the vacancy thus formed, which increases the head of the liquid to a corresponding extent and likewise increases the pressure and the lifting force of the pump.

As the operation of the pump continues, the air is displaced in the sealed or vacuum chamber and replaced with the liquid from one or more of the veins of strata and this

liquid is utilized as though all the space above one lower vein of the liquid were a sealed chamber or vacuum space.

With one vein or strata of liquid at the 5 bottom of the sealed chamber, or with all of the sealed chamber above the line of the liquid, a partial vacuum is created that the pump, regardless of its construction, operates to its full capacity.

10 In operating the pump the small amount of air in the sealed casing is displaced and replaced with and by the liquid in the casing seeking its level therein, thereby producing the same effect that the vacuum would 15 if no liquid took its place and discharged the air left in the sealed chamber.

Initially more or less air is in the sealed chamber, but by the operation of the pump this confined air is displaced and carried out 20 with the liquid and this space replaced with the liquid which rises in the sealed chamber, and this movement is partly governed by the valves of the pump.

25 The full flow of the liquid and the full capacity of the pump is thus assured.

By taking out a percentage of the air in the sealed chamber a suction or pull of the pump rod is created to draw off with the flow, and it is gradually replaced in its re-action 30 by the liquid in the sealed chamber, which after a few strokes of the pump creates a weight to aid the further actions of the pump.

35 The re-action produces an effect similar to a siphon, as the liquid enters the sealed chamber when the pump is idle.

The sealed chamber being filled with liquid, the combination of the water filling 40 in the sealed chamber with the closing of the lower or check valve of the pump, operates as a trap to hold the liquid up in the sealed chamber until the pumping is resumed, and the lower or check valve operates to hold the liquid to enable the plunger to gather its 45 load and elevate it through the pump tube.

By this means the benefit of the ordinary or lifting action is insured by the increased benefit of the excess flow, as above described, and adds the benefit of the increased weight 50 and pressure and maintains an even, uniform, and increased flow of the liquid.

The sealing medium as illustrated in Figure 3, may be disposed at any point within the outer casing, depending upon the number 55 of liquid veins to be tapped, the depth of the well, the power used in the pumping action.

The power required to operate the pump is necessarily increased because of the increased flow of liquid.

60 The improved device may be used for elevating water, oil, or the like wherein the pressure of gas is not sufficient to be utilized for heat or power to force the discharge of the liquid.

65 By the improved apparatus, the full benefit or all underflow of the liquid is utilized to the full capacity of the conductor pipe, as the valves of the pump have no escape except through the latter. The full capacity of the conductor pipe is maintained during the pumping action regardless of where the sealing element is located, whether at the top as shown in Figure 1 or at any intermediate 70 point as shown in Figure 3.

75 The nearer to the liquid the sealing element is disposed the less power will be required to produce the requisite flow.

If a plurality of veins or strata of liquid 80 are encountered, and the casing sealed, the power required to operate the pump is diminished, and the sealing element can be located nearer the line of the liquid, and thus decrease the power required to operate 85 the pump.

The preferred embodiment of the invention is disclosed in the drawings and set forth in the specification, but it will be understood that modifications within the 90 scope of the claimed invention may be made in the construction without departing from the principle of the invention or sacrificing any of its advantages.

Having thus described the invention, what 95 is claimed as new is:—

A device of the character described comprising a pump casing having therein longitudinally spaced groups of openings a closure cap secured on the upper end thereof 100 having an opening therein for the passage of a pump element and a sealing element mounted in the bore of said casing between the uppermost group of openings and the upper end of said casing and having an 105 opening therein for the passage of a pump element, said sealing element being capable of longitudinal adjustment in said casing for the purpose of varying the space between said group of openings and said 110 sealing element, as set forth.

In testimony whereof, I affix my signature hereto.

HENRY C. MORRISON.
